The ornamental design for a portable pneumatic nailer, as shown and described.

DESCRIPTION

FIG. 1 is a perspective view of a portable pneumatic nailer showing our new design, looking at the top, front and left side, the magazine assembly and nosepiece of the device being shown in phantom lines;
FIG. 2 is a left side elevational view thereof, the right side thereof being a mirror image thereof;
FIG. 3 is a front elevational view thereof;
FIG. 4 is a rear elevational view thereof;
FIG. 5 is a top plan view thereof; and,
FIG. 6 is a bottom plan view thereof.

FIG. 4FIG. 3FIG. 5

FIG. 6
